(57) **CLAIM**

The ornamental design for a vehicle driving light, as shown and described.

DESCRIPTION

FIG. 1 is a front isometric view of a first embodiment of the vehicle driving light;

FIG. 2 is a rear isometric view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top plan view thereof; and,

FIG. 8 is a bottom plan view thereof.

The portions of the vehicle driving light depicted in broken dash lines represent the bounds of the claim and form no part of the claimed design.

1 Claim, 7 Drawing Sheets
